UNITED STATES PATENT OFFICE

WALTER McANEAR, OF ELECTRA, TEXAS

TANK CLEANER

Application filed May 9, 1931. Serial No. 536,239.

The present invention relates to a tank cleaner particularly designed for use in cleaning oil storage tanks and the prime object of the invention resides in the provision of a 5 cleaning apparatus which is easy to operate and install, inexpensive to manufacture, thoroughly efficient and reliable in use and operation, strong and durable, and otherwise well adapted to the purpose for which it is 10 designed.

With the above and numerous other objects in view as will appear as the description proceeds, the invention resides in certain novel features of construction, and in the combination and arrangement of parts as will be 15 hereinafter more fully described and claimed.

In the drawings:

Figure 1 is a vertical section through a tank showing the cleaning mechanism therein.

Figure 2 is a horizontal section taken substantially on the line 2—2 of Figure 1.

Figure 3 is a horizontal section taken substantially on the line 3—3 of Figure 1.

Figure 4 is a perspective view of the shaft.

Figure 5 is a vertical sectional view through the cleaning apparatus and particularly through one of the brushes.

Figure 6 is a section taken substantially 30 on the line 6—6 of Figure 5, and

Figure 7 is a detail section through the bearing blocks.

Referring to the drawings in detail it will be seen that the numeral 5 denotes the bottom 35 of the tank from which rises the cylindrical wall 6. A top 7 is mounted on the upper edge of the wall 6 and is formed at its center with a stuffing box 9 through which is journalled a vertical shaft 10. The bottom end of the

40 shaft 10 is formed with a semi-spherical knob 11 adapted to rest in a concave seat 12 formed in the upper surface of a bearing block 14 which is welded or otherwise fixed on the bottom 5. A plate 15 is hingedly mounted as 45 at 16 on the block 14 and has a slot 17 extending from an intermediate portion to the free end thereof so that the shaft 10 may extend therethrough. A bolt 18 is associated with plate to hold the same in a down position.

50 Oppositely extending plates 20 are bolted to

the lower portion of the shaft 10 and are fixed to brush heads 21 which have downwardly disposed bristles 22.

Braces 23 are fixed to the brush heads 21 by the same means 24 as hold the plates 20 thereto and are fastened to the shaft by means 25.

Larger braces 26 are fastened to the shaft as at 27 above the means 25 and are fixed to the brush heads adjacent their outer ends 60 as at 28. The shaft 10 extends above the tank and on its outer upper end is equipped with a hand wheel 29. The bottom of the tank 5 is provided with an opening with a drain valve 30 therein. Obviously by turning the wheel 29 the brushes will clean the bottom settling from the tank without unduly stirring up the oil.

The top 7 is provided with a manhole (Fig. 1) through which the several parts of the device are passed into the tank to be properly assembled by a person within the tank. The manhole also serves as an entrance and exit opening for the tank.

It is thought that the construction, utility, 75 operation and advantages of this invention will now be quite apparent to those skilled in this art without a more detailed description thereof.

The present embodiment of the invention has been described in considerable detail merely for the purposes of exemplification since in actual practice it attains the features of advantages enumerated as desirable in the statement of the invention and the 80 above description.

It will be apparent that changes in the details of construction may be resorted to without departing from the spirit or scope 85 of the invention as hereinafter claimed or sacrificing any of its advantages.

Having thus described my invention, what I claim as new is:

1. In combination with a tank, of a block 95 fixed to the bottom of the tank and having a concave recess in the upper surface thereof, a shaft journalled through the top of the tank and terminating at its bottom end in a knob bearing in the recess, means on the block 100 for holding the knob in the recess, and brush-

ing means on the shaft to engage the bottom of the tank, said means for holding the knob in the recess comprising a plate hingedly mounted on the block at one end and means for holding the other end locked in place, 5 said plate having a slot through which the shaft extends.

2. In combination with a tank, of a block fixed to the bottom of the tank and having a concave recess in the upper surface thereof, 10 a shaft journalled through the top of the tank and terminating at its bottom end in a knob bearing in the recess, means on the block for holding the knob in the recess, and brushing means on the shaft to engage the bottom of 15 the tank, said means for holding the knob in the recess comprising a plate hingedly mounted on the block at one end and means for holding the other end locked in place, 20 said plate having a slot through which the shaft extends, said brushing means comprising a pair of brushes radiating from the shaft, and means for securing the brushes to the shaft.

3. In combination with a tank, of a block fixed to the bottom of the tank and having a concave recess in the upper surface thereof, 25 a shaft journalled through the top of the tank and terminating at its bottom end in a knob bearing in the recess, means on the block for holding the knob in the recess, and brushing means on the shaft to engage the bottom of the tank, said means for holding the knob in the recess comprising a plate 30 hingedly mounted on the block at one end and means for holding the other end locked in place, said plate having a slot through which the shaft extends, said brushing means comprising a pair of brushes radiating from the shaft, and means for securing the brushes to the shaft, the outer end of the shaft having a hand wheel thereon.

In testimony whereof I affix my signature.
WALTER McANEAR.
